UNITED STATES PATENT OFFICE.

WENSEL MORAVA, OF CHICAGO, ILLINOIS.

GAS-SCRUBBER.

SPECIFICATION forming part of Letters Patent No. 388,903, dated September 4, 1888.

Application filed March 3, 1887. Serial No. 229,502. (No model.)

To all whom it may concern:

Be it known that I, WENSEL MORAVA, a citizen of the United States, residing at Chicago, in the county of Cook and State of Illinois, have invented certain new and useful Improvements in Gas-Scrubbers, which are fully described in the following specification, reference being had to the accompanying drawings, forming a part thereof.

10 The purpose of this invention is to provide improved means for extracting ammonia and other impurities from coal-gas, and it belongs to that class of devices which for that purpose take advantage of the fact that ammonia 15 is readily absorbed by water in thin films; and it consists, essentially, of devices by which the greatest possible amount of surface carrying a film of water may be presented to the gas within the least possible compass and in 20 such manner as to offer the least resistance to the passage of the gas through or over the same.

In the drawings, Figure 1 is an elevation of 25 my device, having part of the outer shell broken away and certain parts within shown in axial section. Fig. 2 is a transverse vertical section through the line $x-x$, Fig. 1. Fig. 3 is an end elevation of one compartment or section, several of which are joined together to constitute 30 the entire structure shown in Fig. 1. Fig. 4 is an enlarged longitudinal radial section of a portion of one of the reels or bobbins which form the water-carrying surface. Fig. 5 is an enlarged transverse section of one of said reels or bobbins.

35 In general, my invention comprises a substantially-cylindrical case, preferably made up of sections or separable compartments, as I will hereinafter describe, through the axis of 40 which extends a shaft driven by suitable mechanism exterior to said case, the shaft being journaled in stuffed journal-boxes in the two ends or heads of the case. Each section or compartment of the case contains a reel or bobbin of the structure which I will herein- 45 after describe, such reel being keyed fast to and revolved by the shaft. The several sections or compartments are separated by annular diaphragms, through whose central aperture the shaft passes, leaving considerable 50 space about it for the circulation of gas, as hereinafter described.

It will be observed that the end section A^{11} instead of having an annular diaphragm at the end, has a full head, a^{11} , closing the end of the 55 case, and that the other end section, A^{12} , besides having the annular diaphragm at one end, has the full head a^{12} closing that end of the case.

60 B is the shaft, driven by a gear-wheel, B', exterior to the case and journaled in stuffing-boxes A^2 A^2 , one at each end. Upon the shaft B there is keyed fast in position to revolve in each chamber formed between each two consecutive diaphragms a double bobbin or reel. 65 Each half of this bobbin is composed of a hub, C, a ribbed web, c, and cross-arms C², having at each end annular flanges C³, which are parallel, the flange at the same end of the cross-arms being substantially a continuation of that 70 web, and with it making a complete disk. The two halves of each bobbin are secured together back to back, so that their ribbed webs are in contact, and are secured together by suitable bolts or rivets, thus forming a unitary structure 75 which operates as integral. The outer annular flanges have their central aperture of the same diameter as the central aperture in the annular diaphragm A^{10} of the case. Said diaphragm A^{10} and flanges C³ are preferably 80 provided with a boss or raised edge, which is faced up, so that as the bobbins revolve within the compartments formed by the diaphragms approximately tight junctions may exist where said faced flanges are in contact. 85 Whatever space may by wear come to exist at this point will be practically sealed by the water film, which will constantly adhere to the adjacent surfaces.

89 It will be noticed that the annular flanges of 90 the bobbins, which, together with the central web, constitute continuous disks, are so formed that when the two halves of the bobbin are secured together an annular interval exists between the corresponding flanges of the two 95 halves. The purpose of this is to allow space for the partitions A⁸, which are secured, respectively, in the middle of each chamber, and prevent the free interchange of water between the two parts of the chamber in which the two 100 sections of the bobbin respectively revolve. The purpose of this is to cause the degree of purity of the water in the successive chambers to correspond to the degree of purification

which has taken place in the gas when it reaches the chambers, respectively, so that at all stages the water shall have power to absorb impurities from the gas presented to it. The 5 partitions A⁸ may be omitted with no loss except of that advantage, and, so far as they relate to the circulation of the gas or have any function in connection with such circulation, said separated flanges may be considered as 10 one and as forming simply a disk dividing between the two parts of the bobbin. Upon these bobbins I wind the wire D, as illustrated in Figs. 4 and 5, in successive layers, which are separated by slats E, said slats being preferably placed in radial line with the spokes C⁹, continuing this process until the bobbin is full; or I use wire-cloth cut the full width of the space between the flanges C⁹ and wound in like manner, with spacing-slats E interposed at each successive coil, until the bobbin is full. I consider the wire and the wire-cloth substantially equivalents, but prefer the latter for the greater surface which it affords and the greater ease in applying and removing for 15 cleaning. When the wire is used, I coil it in such manner as to leave more lateral space between successive turns at the inner or central part of the bobbin than toward the outer part, increasing thus the closeness of the coil as the 20 diameter of the same increases; and in case I use the wire-cloth I use more openly-meshed cloth at the inner portion of each bobbin than toward the outer part, increasing thus the fineness or closeness of the web as I wind more 25 onto the bobbin, and the diameter of the coil thereby increases.

The operation of this device is as follows: Water being admitted into the case and standing at such depth as approximately to cover 30 the width of the annular flanges on the bobbins, as at the line v v in Fig. 1, rotary motion being given to the shaft B, the wire or wire-cloth coils on the bobbins revolving in the water will become thoroughly wetted. 35 The gas, being now admitted through the induction-pipe A⁴, passes through the central aperture in the first diaphragm A¹⁰, and thence into the center of the adjacent half of the first bobbin, from which it can only escape by passing upward or radially outward through the 40 meshes of the wire or web on the bobbin. Having passed through this, it fills the annular space A⁵ outside the bobbin within the first section or compartment of the case A; and 45 from this annular space there is no escape except by passing back toward the center of the said first bobbin through the meshes of wire or web coil which fills the second half of the bobbin into the central clear space of 50 the same, from which it will pass in like manner into and through the second bobbin, and thus through the successive bobbins to the end of the case, and thence out through the eduction-pipe A⁷, passing in each instance 55 in at the center and radially through the wetted coils to the periphery, and thence back through the wetted coils to the center. The

bobbins, being in constant revolution, and being, therefore, constantly freshly wetted, present constantly fresh surfaces of the absorbent film of water to the ammonia-charged gas. The water at the end at which the gas passes out, being water which has just entered, and is therefore the purest in the entire case, encounters the gas which has passed through all 75 the preceding bobbins, and is therefore most nearly purified, but encountering the perfectly pure water just entering, it will still yield up its small remnant of ammonia thereto, whereas, if it should at that stage encounter water 80 already heavily charged with ammonia, it might even reabsorb ammonia therefrom.

It is desirable that the resistance to the passage of the gas through the apparatus should be substantially constant and uniform at all 85 parts of its course, for two reasons: first, because the flow under given pressure can be no faster than that which such pressure will produce past the point of greatest resistance, and, second, a change of resistance, and consequently of local tension of the gas, is found to cause it to deposit its illuminating elements, causing diminution of its illuminating-power and clogging the apparatus. For this reason the above-described structure is employed, 90 viz: spacing the wire or mesh more openly in the coils nearer the center of the bobbin than toward the circumference. In order to produce the precise effect sought, the space in successive coils should be inversely proportional 95 to the diameter of the coil. This effect may be produced by increasing the diameter of the wire and making the same number of turns of it, or by merely diminishing the width of the spaces, and so increasing the number of turns 100 made in each coil as the diameter increases. An apparatus for this purpose becomes clogged with impurities which it will gather from the gas and from the water. The form of this 105 clogging will usually be an incrustation on the wire or web. In order to remove this and keep the apparatus in constantly effective condition, each compartment of the case A' is provided with an opening, a¹⁰, through which the web or wire forming the coil upon the bobbin within that compartment may be withdrawn, being 110 for that purpose wound upon a reel outside of the case, in which process of unwinding and rewinding the impurity forming an incrustation will usually be completely detached and 115 the desired cleansing effected; but, if found necessary, it can be brushed as it is unwound from the bobbin. To rewind it, it is only necessary to give the shaft B proper rotary motion and so unwind the web from the exterior 120 temporary reel on the bobbin within the case. 125

In securing the halves of each bobbin together a provision may be made for such slight adjustment as may be necessary in order to make the reels fit closely within their respective compartments of the case A and make gas-tight junctions at the bosses on the diaphragms A¹⁰ and the flanges C⁹. This I do by providing screws c', which are set through the 130

web C' on one of the halves of the bobbin and against the surface of the like web on the other part, and providing also screws c¹⁰, which pass through one web and are screwed into the other, 5 and so fasten them together. By screwing the screws c' farther through the web in which they are held, and at the same time slackening the clamping-screws c¹⁰, the two halves of the bobbin or reel may be forced apart and its 10 bosses on the flanges C³ made to fit the bosses on the diaphragms A¹⁰ as closely as desired.

I am aware of the device patented to W. A. Simonds, June 21, 1864, Patent No. 43,264, and I do not wish to be understood as claiming 15 anything shown in his said patent.

I claim—

1. In a gas scrubbing machine, in combination with the case, a reel or bobbin inclosed in such case, and the water-holding fabric 20 wound thereabout in circumferential coils, with intervals between the successive coils or layers, and removable by simply unwinding, substantially as set forth.

2. In a gas scrubbing machine, in combination with the case, woven-wire cloth or web, 25 serving as the water-holding fabric, wound about a bobbin in circumferential coils radially successive and removable by simply unwinding, and suitable mechanism to revolve the bobbin about its axis, substantially as set forth.

3. In a gas scrubbing machine, in combination with the case, a reel or bobbin inclosed in the case, a water-holding fabric wound 35 thereabout in circumferential layers, a circumferential series of strips unattached to the bobbin being interposed between each layer and the next succeeding layer, the several successive series of such strips containing each the 40 same number of strips, each strip being in radial line with the corresponding strip of the preceding series, whereby said strips become arranged in radial piles and support the water-holding fabric in concentric layers, with intervals between the concentric layers, and render said fabric detachable from the bobbin 45 by simply unwinding, substantially as set forth.

4. In a gas-scrubbing machine, in combination with the case, woven-wire cloth or web, 50 serving as the water-holding fabric, wound about the bobbin in circumferential layers radially successive and separated by successive series of strips, the strips of each series being applied at intervals in the circumference about 55 each layer of the wire-cloth and being unattached to the bobbin, the several successive series containing each the same number of strips, each strip being in radial line with the corresponding strip of the preceding series, 60 and suitable mechanism to revolve the bobbin about its axis within the case, substantially as set forth.

5. In combination with the case having compartments to which the gas is admitted about 65 the center, the reels or bobbins and suitable mechanism to revolve them in such compart-

ments, said reels or bobbins comprising each a disk continuous from the center to the periphery and of less diameter than the case, and the water-holding fabric arranged in two 70 masses, one on either side of such disk, whereby the gas entering the compartment on one side is compelled, in order to escape at the other side, to pass around the central disk by passing through one mass of wetted fabric while 75 moving toward the periphery and through the other mass while moving back toward the center, substantially as set forth.

6. In combination with the case having annular partitions, the reels or bobbins in the 80 case and suitable mechanism to revolve them, said bobbins or reels comprising each a disk continuous from center to periphery, and lateral annular disks which revolve closely adjacent to the annular partitions of the case, 85 and two masses of water-holding fabric located, respectively, between the annular disks and the continuous disk, substantially as set forth.

7. In a gas-scrubbing machine, in combination, substantially as set forth, the case, the axial shaft therein, the water-holding fabric circumferentially wound on suitable supports connected to the shaft, the case having lateral apertures corresponding to the longitudinal 95 position of the water-holding fabric, whereby such fabric may be withdrawn from the case by unwinding it from its supports and may be rewound on such supports within the case by 100 revolving the shaft.

8. In a gas-scrubbing machine, the reels or bobbins having apertured water-holding fabric wound thereon in successive concentric layers or courses, with interspaces, the total extent 105 of the apertures being substantially the same in each of the successive layers or courses, substantially as set forth.

9. In a gas-scrubbing machine, the bobbins having wire fabric wound thereon, with spaces between the successive courses, the inner 110 courses having more open mesh than the outer, the fineness of the mesh increasing as the courses proceed from center to periphery, substantially as set forth.

10. In combination with the case having the annular diaphragms A¹⁰, the bobbins having the flanges C³, whose remote lateral surfaces are contiguous, respectively, to the proximate lateral surfaces of consecutive diaphragms, said bobbins being made in halves, 115 each half having one of the flanges C³ and secured together by screws c¹⁰, the adjusting-screws c' set through the web of one of the halves against that of the other, substantially 120 as set forth.

In testimony whereof I have hereunto set my hand this 24th day of February, A. D. 1887.

WENSEL MORAVA.
